UNITED STATES PATENT OFFICE.

ERNST FRIEDEZKY, OF TROPPAU, CZECHOSLOVAKIA, ASSIGNEE TO THE FIRM RASIER-KLINGENFABRIK "RIVO" HAHN, RICHTER & VOLKMANN, OF TROPPAU, CZECHOSLOVAKIA.

DEVICE FOR SHARPENING PENCILS.

Application filed July 26, 1927, Serial No. 208,569, and in Austria March 31, 1927.

This invention relates to improvements in devices for sharpening pencils, in which a used safety razor blade is employed as a cutter, and it has for its object to provide means 5 for supporting and holding the blade to secure an efficient cutting action and to render possible the correct adjustment of the blades, which are not always of exactly the same size, and further to secure a firm clamping 10 of the blade in position.

One mode of carrying out the present invention is illustrated by way of example on the accompanying sheet of drawings in which.

15 Figs. 1 and 2 show in front view and plan view respectively a pencil-sharpener embodying my invention the tensioning plate being removed.

Fig. 3 illustrates in transverse section the 20 sharpener with the tensioning plate secured in position, the section being taken on line III-III of Fig. 2.

Fig. 4 is an inverted plan view of the tensioning plate, and

25 Fig. 5 is a transverse section through a portion of the sharpener on an enlarged scale.

The guide sleeve 1, provided with a conical bore to receive the point end of the pencil, 30 is furnished at one side of the shavings outlet slot with an extension in the shape of a base plate 2, which is provided with a plain bearing surface for a bearing plate 3, furnished with a handle 4. The bearing surface is arranged so as to dispose the outer face of the plate 3 outside of the tangential plane which passes through the generatrix of the guide-sleeve and above the cutting plane. The two plates are connected with one another in 40 such a manner by screws 5, 5', passing through transverse slots 6 of the plate 2, that they can be moved with respect to one another in the direction transverse to the sleeve. The plate 3 is provided with two projections 45 or raised parts 7, 7', corresponding with the outer holes of a safety razor plate provided with three holes (Gillette type). By means of the projections 7, 7', a blade placed upon the plate 3 is prevented from shifting with respect to the plate 3 in the direction of its adjustment, so that the plate 3 and the blade 50 form a unit. At its inner side the plate extends but slightly beyond the holes of the

blade, so that one edge portion of the blade projects without support materially beyond this side of the plate. The end portions of the cutting edge of the blade, when the latter is in cutting position, rest against two smooth abutment faces 9 of the sleeve, which lie in a plane passing through the axis of the sleeve-bore vertically with respect to the plates 2, 3. Below the centre hole of the blade, the plate 3 is provided with an opening 10 and the plate 2 is furnished with a suitable screw-threaded hole 11, in order to secure a tensioning plate 65 12 by means of a screw 13. At its inner edge, the tensioning plate is provided with a wedge-shaped extension 14, which bears upon the blade near its cutting edge and depresses the latter into the slot of the guide-sleeve, 70 so that shavings or chippings are cut off of the rotated pencil, the shavings passing out of the sleeve by way of its discharge slot. The clamping of the blade, whereby the latter is bent, effects an advantageous stiffening 75 of the thin blade and its tensioning, as will be readily understood. Preferably the arrangement is such, that, when the blade is correctly tensioned, the bottom face of the cutting edge is disposed parallel with respect to the tangential plane passing through the generatrix of the sleeve-bore above the cutting edge. The disposing of the plate 3 upon the plate 2 renders possible also the use 80 of greatly worn blades, which have been rendered irregular by frequent grinding. After sliding the blade against the bearing surfaces 9, the screws 5, 5' can be tightened, so that on applying the tensioning plate and fixing the same by means of the screws 13, the blade 85 cannot be shifted in any way.

I claim—

1. A pencil sharpener for use in connection with safety razor blades provided with two or more holes, comprising a guide sleeve having a conical bore and a slot communicating therewith, an extension at one side of said sleeve and parallel with said slot, a bearing plate resting on the extension of the sleeve and having a blade supporting surface lying outwardly beyond the tangential plane extending through the generatrix of the guide lying outwardly beyond the cutting plane, said plate having projections to engage the openings in the blade, a blade resting on the 100 supporting surface of the bearing plate and 105

having a portion thereof provided with a cutting edge projecting laterally beyond that edge of the bearing plate facing the slot so as to dispose said cutting edge in alinement with the slot, a tension plate resting upon the blade and having means for bending the projecting portion thereof at an inward and downward angle tangential to the generatrix of the sleeve, and means for securing said tension plate in position.

2. A pencil sharpener of the character set forth in claim 1 wherein the extension and

bearing plate are provided with interengaging slots and projections to permit adjustment of the blade with relation to the slot. 15

3. A pencil sharpener of the character set forth in claim 1 wherein that side of the slot opposite the extension is formed with a recess and surfaces at the ends of said recess against which the end portions of the cutting edge 20 of the blade bear.

In testimony whereof I affix my signature.

ERNST FRIEDEZKY.
